US0D1048952S

(12) **United States Design Patent** (10) **Patent No.:** **US D1,048,952 S**
(45) **Date of Patent:** **** Oct. 29, 2024**

(54) **DRIFTING KART**

(71) Applicant: **Ali Kermani**, Huntington Beach, CA (US)

(72) Inventor: **Ali Kermani**, Huntington Beach, CA (US)

(**) Term: **15 Years**

(21) Appl. No.: **29/841,221**

(22) Filed: **Jun. 3, 2022**

Related U.S. Application Data

(63) Continuation of application No. 29/774,679, filed on Mar. 18, 2021, now Pat. No. Des. 953,939, which is a continuation of application No. 29/698,467, filed on Jul. 17, 2019, now Pat. No. Des. 913,878, which is a continuation of application No. 29/604,471, filed on May 17, 2017, now Pat. (57) **CLAIM**

The ornamental design for a drifting kart, as shown and described.

DESCRIPTION

FIG. 1 is a top, front, and left side perspective view of a drifting kart embodying my new design;

FIG. 2 is a right side elevation view thereof;

FIG. 3 is a front elevation view thereof;

FIG. 4 is a rear elevation view thereof;

FIG. 5 is a top plan view thereof; and,

FIG. 6 is a bottom plan view thereof.

The broken lines in the drawings illustrate portions of the drifting kart that form no part of the claimed design.
